UNITED STATES PATENT OFFICE.

HARVEY P. WELLMAN, OF OAKLAND, CALIFORNIA.

NUMERATING AND RECORDING MACHINE.

1,259,325.

Specification of Letters Patent. Patented Mar. 12, 1918.

Original application filed November 7, 1914, Serial No. 870,791. Divided and this application filed August 9, 1916. Serial No. 113,936.

To all whom it may concern:

Be it known that I, HARVEY P. WELLMAN, a citizen of the United States, residing at Oakland, in the county of Alameda and 5 State of California, have invented new and useful Improvements in Numerating and Recording Machines, of which the following is a specification.

This invention relates to a machine for 10 counting various articles as they pass a given point, and for making an accurate record as to their character, number, size, quality, etc., and pertains especially to a machine for counting and making a record 15 of cans in fruit packing establishments and elsewhere.

Canned goods, in the course of packing or being made up in the factory and before they are labeled, are indistinguishable one 20 class from another, and one can from another, and it has heretofore been a source of a great deal of difficulty and confusion to keep track of the hundreds of different varieties and different grades of goods 25 packed and different grades and weights of syrup used in making up the contents day by day. In view of this difficulty and the demand for a machine which will to a large degree automatically count and record not 30 only the individual articles handled, but the various grades, weights and qualities of articles, I have devised the mechanism herein-after described.

The invention consists of the parts and 35 the construction and combination of parts as hereinafter more fully described and claimed, having reference to the accompanying drawings, in which—

Figure 1 is a detail view of a finished 40 record.

Fig. 2 is a plan view of the recording device and means of operation.

Figs. 3 and 4 are cross sections on line 3—4, Fig. 2, showing passing can and passing 45 of dummy can.

Fig. 5 is a perspective view of a dummy can.

Fig. 6 is a section of an adjustable dummy can.

50 Fig. 7 is a side elevation of the recording machine, with case in section.

Fig. 7^a is a detail plan view of the clearance lever detent on the case.

Fig. 8 is a vertical, longitudinal section on line 8—8, Fig. 10. 55

Fig. 9 is a detail view of the printing mechanism operating levers.

Fig. 10 is a vertical, transverse section on line 10—10, Fig. 8, looking in the direction of the arrow. 60

Fig. 11 is a detail perspective view of the clearing dogs.

Fig. 12 is a perspective view of the carrying wheels.

Fig. 13 is a detail perspective view of the 65 ribbon reeling mechanism.

Fig. 14 is a detail elevation of the index disks.

Fig. 15 is a horizontal section on line 15—15 of Fig. 14. 70

It will be manifest that while I have shown and described the invention in its particular adaptation to the fruit canning industry, the apparatus is applicable to a great variety of uses. 75

The invention comprises generally coördinated counting and printing mechanisms arranged to be operated at the will of the attendant by the cans or special tokens passing out of the sealing machine, or as they 80 pass any given point in the operation of packing; it being desirable that this point be near the last operation in the sealing or packing machine.

Referring to Fig. 2, A represents the packing machine, can carrier or other source of supply for the cans which are to be counted, and B a case situated at any suitable point more or less remote from the cans, and containing the counting, classifying and 85 recording mechanism hereinafter to be described. 2—2 represent counted cans; 3 a yet unrecorded can and 4 a dummy can or token for operating the marking or printing mechanism, as hereinafter described. The 90 cans 2 as they progress in their travel operate the count mechanism trigger 5, (see especially Figs. 2 and 3) while the dummy can 4, Figs. 2—4 has an upwardly projecting pin 6 adapted to engage the marking 100 mechanism trigger 7 placed in the plane above the level of the top of a can, as shown

in Fig. 3; the dummy can 4 having a peripheral groove 8 which permits it to clear the counting trigger 5. It is understood that the dummy can 4 is only sent through the machine at the end of a run of a certain size, variety, grade or quality of article being packed.

A machine of this nature being subjected to trying conditions in the factory, due to 10 temperature changes and moisture in the atmosphere, etc., must be simple and substantially built, avoiding as far as possible the use of small springs, and unnecessary cumbersome devices. It is also important 15 that a recording mechanism of this sort be so constructed as to be rendered adjustable to prevent either under-carrying or over-carrying.

Referring to Figs. 10 and 8, 10 represents 20 a stationary shaft journaled in casing B and forming an axis for the train of count wheels 11, 12, 13, 14 and 15, and for the concentric shafts 16, 17 and 18, which carry the respective can marking wheels 19, 20 and 21; 25 all these several wheels being suitably spaced from each other and from the wall of casing B by suitable spacing washers 22. The marking wheels 19, 20 and 21, with their hollow shafts and the count wheels 11, 12, 13, 30 14 and 15, are all free to turn on the central stationary shaft 10; the count wheels 11, 12, 13, 14 and 15 constituting a group by themselves and the marking wheels 19, 20 and 21 constituting a group by themselves and yet 35 all of the wheels at the proper time operating as marking wheels since each and all of these wheels are provided with type faces 23 on their periphery adapted to coöperate with a platen roll 24 and suitable inking mechanism, all in the manner hereinafter to be described.

The marking wheels 19, 20 and 21 (so-called because by them the appropriate can marks, such as weight, variety, and grade are indicated) are actuated from the outside of 40 the machine, while the counting wheels proper, 11 to 15 inclusive, are operated in train from the counting trigger 5, as will be shortly explained. I have shown two modes 45 of actuating the marking wheels 19, 20 and 21: In Figs. 14 and 15 there is shown the preferred method in which the hollow shafts 16, 17 and 18 connect with respective indicator dials 26, 27 and 28 on the outside of the 50 casing B. These dials are provided with suitable markings according to the variety and nature of the goods handled. The outside dial 28 is marked to indicate size or weight; the next adjacent dial 27 may be 55 marked to indicate the variety of goods packed, one letter standing, say, for peaches, another letter standing, for example, for apricots, and so on; and the inner dial 26 marked to indicate grade or quality, or 60 goods known under some special brand or

mark. These three dials 26, 27 and 28 are each independently movable with relation to a fixed indicator or pointer 30. The operator brings these dials opposite the pointer, according to the run through the machine, and 70 the lettering or figures appearing opposite the pointer 30 are duplicated by the type face on the marking wheels 19, 20 and 21 at a point directly opposite the platen roller 24 so that whenever the printing trigger 7 is 75 actuated by a dummy can there will be printed a record on a paper strip 31 which will show the total number of cans of that particular run of goods of that particular variety, weight and grade or quality. 80

In Figs. 7 and 10 I have shown an alternative method of operating the marking wheels 19, 20 and 21 wherein the hollow shafts 16, 17 and 18 extend to different distances outside the casing and carry indicator fingers 34, 35 and 36, which move over corresponding dials 37, 38 and 39; the only difference between the design of Fig. 7 and that of Fig. 14 being that in one case there are three movable pointers operating over 90 three fixed dials and in the other case there are three movable dials movable with respect to one fixed pointer. The dials in Figs. 14 and 15 are maintained in place by suitable friction devices as the spring-pressed balls 95 40 seated in the pointer 30 engageable in depressions 41 in the dials.

Each of the denominational count wheels 11, 12, 13, 14 and 15 is loose on the shaft 10 and is provided on one side with an annular 100 series of twenty projecting pins or lugs 45; each count wheel having on its opposite side a single pin or lug 46. Between the respective pairs of count wheels 11—12, 12—13, 13—14, 14—15, is a carrying or transfer 105 wheel which is made in two complementary, symmetrical parts 47—48 divided in a plane at right angles to its axis, but, obviously may be of the usual form. The parts or wheel sections 47—48 will be actuated once with 110 every revolution of the unit wheel 11. This will serve to advance the tens wheel 12 one step, or one-tenth of a revolution, and so on through the train. Making the transfer wheel 47—48 in two parts is an important 115 feature of the invention, because it allows take-up and provision for wear from time to time, without resorting to the crude methods of filing, bonding prongs, etc., necessary in other machines. 120

A handle 61 is provided to move the bank of carrying wheels 47—48 out of register with the corresponding pins 45—46 of the count wheels in order to allow the count wheels to be cleared, or all brought back to 125 zero as is necessary at the beginning of any fresh run. When the lever 61 is rocked to disengage the carrying wheels 47—48 from the count wheels, thus placing the parts in the position indicated in dotted lines at the 130

left of Fig. 8, the count wheels are in position to be cleared and all brought back to zero.

Any appropriate method or means of operating the count wheels from the count wheel trigger 5 may be employed. In the present instance I have shown a mechanical connection in the form of a pull rod 70 leading from the trigger 5 to and through the case B and connected to a rocking lever 71, Fig. 8; lever 71 carrying a spring actuated pawl 72 engaging step fashion a ratchet wheel 73 on the units wheel 11. Trigger 5 operates the rod in one direction against the action of a spring 74, Fig. 7. Each actuation of trigger 5 thus turns the count wheel 11 one step; ten steps equaling one revolution and one revolution of wheel 11 acting through the carrying wheels 47-48 to move the tens wheel 12 one step, etc., all as before described.

The printing and recording mechanism embodies platen roll 24, the paper strip 31 and the inking ribbon 82, which latter is adapted to traverse the type faces 23 when the latter are in opposition to the rocking platen 24. Platen 24 is mounted on a rocking frame 83 fulcrumed at 84 so as alternately to be moved from inoperative full line position (Fig. 8), to dotted line printing position when it is desired to make a record on the record sheet 31. Any appropriate means of connection may be employed between the recording trigger 7 and the rocking platen frame 83 in order to actuate the platen. In the present instance I have shown a mechanical connection comprising a pull rod 85 which extends through and into case B and connects with one arm of bell crank 86. The other arm of the bell crank is connected by a link 87 with a projection 88 on the frame 83; the link and its corresponding bell crank arm acting toggle-fashion to pull the platen frame and the platen forward toward the count wheels when trigger 7 is actuated by dummy or token can 4. At the same time the platen is given a step by step movement by means of a link 90 and a pawl and ratchet mechanism 91. Tension on the paper and retarding of the rotary movement of the platen roll 24 is effected by the usual spring actuated adjustable rollers 92. The operating mechanism for the platen roller 24 is such that its movement is most rapid at the beginning of a pull on rod 85, finishing with a slow movement and increased leverage as the bell crank arm and link 87 reach almost dead center; thus giving a heavy pressure on the paper against the type and insuring a perfect imprint.

The type 23 are inked by the typewriter ribbon 82, which latter runs from one roller 95 to a ratcheted roller 96; the latter being operated by a suitable pawl and ratchet mechanism 99, (Fig. 8) and link connections

98 with rocking platen frame 83, so that after each imprint the ribbon is given a step forward movement.

Operation.

70

First the machine is cleared so as to set the count wheels at zero by manipulating the lever handle 61 to remove the carrying wheels 47-48 out of contact with the pins 45 and simultaneously to interpose the stop pawls 55 in the path of the single pins 46; it being remembered that there are twenty of the pins 45 on one side of each count wheel all facing in one direction, and a single pin 46 on the opposite side of each count wheel. This operation of the lever 61 brings the key stem 67 into alinement with the keyhole 68 in case B to allow a key 69 to be inserted for the purpose of turning the brushes 66. These brushes 66 simply slip over the studs or pins 45-46 until the clearing operation is completed, after which the lever 61 is moved back to initial position bringing the parts in readiness to act. Lever 61 is maintained in either of its desired positions by appropriate means, as a hinged stop plate 61^a (Figs. 7 and 7^a).

Next the dials 26, 27 and 28, or indicators 34, 35 and 36, according to the style of the machine, are manipulated to indicate the nature of the run of goods. Taking the style of machine shown in Figs. 14 and 15, if the machine is to record a run of canned fruit of 2-1/2 lb. cans, dial 28 is turned to bring the notation "2-1/2" opposite pointer 30. 100 This correspondingly causes the can marking wheel 19 to present its type face "2-1/2" opposite the platen roller 24. The other two dials 26 and 27 are similarly turned to indicate the character and quality or brand of fruit, here represented by the characters "G" and "I". This setting of the machine similarly sets the can marking wheels 20 and 21, with their type face "G" and "I" alined with the type face "2½" on the wheel 19 and all 110 opposite the platen roller 24. Of course this setting of the can marking wheels may take place at any time prior to the actual passing of the dummy can 4 through the machine. During the run of cans each can as it passes trigger 5 actuates the latter and correspondingly operates through the push rod 70 and ratchet and pawl mechanism 71, 72 and 73 the units count wheel; at each operation throwing the centering cam 79 in 120 between two adjacent pins 45; the carrying forward from one count wheel to another being effected by the carrying wheels 47-48.

At the end of a special run the record is printed on the paper strip 31 by passing 125 the dummy can 4 through the machine; the pin 6 on the latter striking trigger 7, pulling the rod 85 and bringing the platen roll paper forward into printing contact with the alined type face on the several count 130

wheels and marking wheels with the interposed inking ribbon 82. This dummy can 4 is so constructed that it will not actuate the counting mechanism as it is not desired to count the dummy can. It is for that reason that the groove 8 is provided in the dummy can to allow it to clear the counting trigger 5.

10 In machines where cans of different sizes are run from time to time I may employ a style of dummy can shown in Fig. 6, wherein in the slot 8' is made adjustable by means of the removable rings 4'. Pin 6' in Fig. 6 and pin 6 in Fig. 5 are each spring mounted 15 so as to be pushed down into the body of the dummy when passing under the heading or sealing mechanisms of the sealing machine. I have not shown pin 6 in the perspective view of Fig. 5 as being spring seated, but 20 it is understood that its mounting is the same as that shown in Fig. 6.

The final results of the machine are shown by the printed record illustrated in Fig. 1; the entire recording mechanism being covered by a case is rendered incapable 25 of being tampered with by any unauthorized person. An operator or employee from the office or accounting department of a canning institution may insert blank paper 30 in the machine daily, or as often as reports may be required, and may in turn remove these reports, placing in new blanks, thus leaving all the details of making up the report to the machine.

35 Many changes in the construction and arrangement of the several parts of the device may, obviously, be employed without departing from the spirit of my invention, as disclosed in the appended claims.

40 This application is a division of my pending application numerating and recording machine, filed Nov. 7, 1914, Ser. #870,791.

Having thus described my invention, 45 what I claim and desire to secure by Letters Patent is—

1. In a can recording mechanism, the combination with a can carrier of a counting and recording mechanism remote from 50 the carrier, and separate means traveling along the carrier for independently operating the counting and recording mechanism from the carrier.

2. A can recording mechanism consisting 55 of a carrier for the cans, a counting and a classifying mechanism located remote from the carrier, said mechanisms provided with type face, means for taking an imprint simultaneously from the type face of the 60 counting and classifying mechanisms, and mechanisms for operating the counting mechanism and printing mechanism from means on the carrier.

3. In a can recording mechanism the 65 combination of a counting mechanism and a

classifying mechanism each provided with type face bearing wheels, a printing mechanism coöperating with the type face, means for operating the count wheels from the cans on the carrier, and means for operating the printing mechanism from the carrier without operating the counting mechanism. 70

4. In a can recording mechanism the combination of a can carrier and a recording mechanism, and a printing mechanism, said recording mechanism including wheels with type face, means for operating the recording wheels from the traveling cans on the carrier, and means for operating the 80 printing mechanism to print the record on the recording wheels from traveling means on the carrier without operating the recording wheels. 85

5. In a can recording mechanism the combination of a can carrier and a recording mechanism, and a printing mechanism, said recording mechanism including wheels with type face, means for operating the recording wheels from the cans on the carrier, 90 and means for operating the printing mechanism to print the record on the recording wheels from means on the carrier without operating the recording wheels, said last-named means including a traveling can 95 token.

6. In a can recording mechanism the combination of a can carrier and a recording mechanism and a printing mechanism, said recording mechanism including wheels 100 with type face, means for operating the recording wheels from the cans on the carrier, means for operating the printing mechanism to print the record on the recording wheels from means on the carrier without 105 operating the recording wheels, said operating means for the recording and printing mechanism including two trigger members arranged at different levels proximate to the path of travel of articles on the carrier. 110

7. In a can recording mechanism the combination of a can carrier and a recording mechanism and a printing mechanism, said recording mechanism including wheels with type face, means for operating the recording wheels from the cans on the carrier, 115 means for operating the printing mechanism to print the record on the recording wheels from means on the carrier without operating the recording wheels, said operating means for the recording and printing mechanism including two trigger members arranged at different levels proximate to the path of travel of cans on the carrier, and a grooved token can adapted to engage one 120 trigger and miss the other. 125

8. In a can recording mechanism the combination of a can carrier and a recording mechanism and a printing mechanism, said recording mechanism including wheels 130

with type face, means for operating the recording wheels from the cans on the carrier, means for operating the printing mechanism to print the record on the recording wheels from means on the carrier without operating the recording wheels, said operating means for the recording and printing mechanism including two trigger members arranged at different levels proximate to the path of travel of cans on the carrier, and a grooved token can adapted to engage one trigger and miss the other, said groove being adjustable.

9. In a recording mechanism, the combination of a series of recording wheels having type face and a rocking platen movable toward and from the type face, a can carrier, and means by which articles on the can carrier operate successively to position the type face in front of the platen and to move the platen to cause an imprint to be made from the type face so positioned.

10. In a can recording mechanism, the combination of a series of count wheels and a series of can marking wheels which are coaxial with the count wheels, type face on the several wheels, a printing mechanism, a can carrier, automatic means for operating the count wheels from the carrier, means for manually operating the can marking wheels, and means for automatically operating the printing mechanism from the carrier to make an imprint simultaneously from the count wheels and can marking wheels.

11. In a can recording mechanism, a series of independently manually adjustable can marking wheels having type face on their periphery, a printing mechanism, a can carrier, and means for automatically operating the printing mechanism from the carrier.

12. In a can recording mechanism in combination, a series of count wheels, a series of manually operable classifying wheels indicating the grade of the cans recorded, and means actuated by said cans for operating said count wheels to record the number of cans of each grade.

13. In a can recording apparatus, the combination with a can delivery mechanism, of a counting device operable by said delivery mechanism to register the number of cans delivered, a classifying register adjustable to indicate the grade of goods in the cans, and a printing attachment operable by said delivery mechanism to record the number and grade exposed by said counting device and classifying register.

14. In a can recording apparatus, the combination with a can delivery mechanism, of a counting device operable by said delivery mechanism to register the number of cans delivered, a classifying register adjustable to indicate the grade of goods in the cans, and a printing attachment operable by said

delivery mechanism operable to record the number and grade exposed by said counting device and classifying register.

15. In a can recording apparatus, the combination with a can delivery mechanism, of a classifying register adjustable to indicate by symbol the grade of goods in the cans, and a printing attachment operable by said delivery mechanism to record the symbols exposed by said classifying register. 70

16. In a can recording apparatus, the combination with a can delivery mechanism, of a manually operable classifying register adjustable to indicate by symbol the grade of goods in the cans, means for counting the number of cans delivered of each grade, and a printing attachment operable independently of said counting means to record the symbols and numbers exposed by said classifying register and counting means respectively. 80

17. In a can recording apparatus, the combination of a classifying register adjustable to indicate by symbol the different grades of goods contained in the cans, said register comprising a plurality of character wheels, means for turning them independently to expose a variety of combinations of symbols, and a printing device independently movable into engagement with said wheels and said counting means to imprint their exposed characters on a tab. 90

18. In a can recording apparatus, the combination of a classifying register adjustable to indicate by symbol the different grades of goods, said register comprising a plurality of printing wheels provided on their peripheries with type symbols, indicator devices each connected with a printing wheel and movable independently to expose a variety of combinations of symbols on said printing wheels, means for counting the number of cans delivered of each grade, and a printing platen independently movable into engagement with said wheels and said counting means to imprint their exposed characters on a tab. 105

19. In a can recording apparatus, the combination of a classifying register adjustable to indicate by symbol the different grades of goods, said register comprising a plurality of printing wheels provided on their peripheries with type symbols, a dial for each of said printing wheels having characters to correspond therewith, a pointer for each of said dials, one of said parts being connected to the corresponding printing wheel whereby to set the same and expose a variety of combinations of symbols in printing position, means for counting the number of cans delivered of each grade, and a printing platen independently movable into engagement with said wheels and said counting means to imprint their exposed characters on a tab. 115

20. A device for recording packaged goods, comprising the combination with package carrying means, of means operated by devices on the package carrier for making a permanent record of both the total number and quality or kind of goods transported.

In testimony whereof I have hereunto set my hand in the presence of two subscribing witnesses.

HARVEY P. WELLMAN.
